CLAIM

The ornamental design for an electrical energy distribution device, as shown and described.

DESCRIPTION

FIG. 1 is a left side view of an electrical energy distribution device, showing our new design;

FIG. 2 is a rear view thereof;

FIG. 3 is a top plan view thereof;

FIG. 4 is a perspective view thereof;

FIG. 5 is a left side view thereof in an unfolded position;

FIG. 6 is a perspective view thereof in an unfolded position; and,

FIG. 7 is a rear view thereof in an unfolded position.

The broken lines and the areas within them represent portions of the electrical energy distribution device and form no part of the claimed design.
